3 Claims. (Cl. 250—213)

This invention relates to light intensifiers for radiations, and particularly for those having high transmittivity, such as X-rays, γ -rays, etc.

The primary object of the present invention is to provide a light intensifier of the kind specified in which radiation energy is more efficiently utilized than ever, the sensitivity of the photoconductive element is never lowered by mechanical working, and impedance conditions are also improved.

The above objects are accomplished by the inclusion of a radioluminescent layer in the device for converting the incident X-rays to visible radiation which then impinge upon a photoconductor-electroluminescent light amplifier.

There are other objects and particularities of the present invention, which will be made obvious in the following descriptions, with reference to the accompanying drawings, in which:

FIG. 1 is a longitudinal sectional view of a light intensifier embodying the present invention, with the electrical supply circuit shown diagrammatically; and

FIG. 2 is a perspective view of another embodiment of the invention, partly cut away to show the internal construction, with the electric supply circuit shown diagrammatically.

In general, a photoconductive layer is low in transmittivity of optical rays. As a result, a photoconductive layer effectively absorbs the energy of optical rays irradiating the same. In other words, a photoconductive layer has a high utilization factor of optical ray energy and is effectively excited thereby. Thus a photoconductive layer has a high photoconductive sensitivity, in general.

On the other hand, a photoconductive layer shows a certain degree of photoconductivity with respect to radiations, such as α -rays, γ -rays, etc. However, the high transmittivity of such radiation causes the same to pass through the photoconductive layer, with only a small portion being absorbed in the latter, resulting in low energy utilization factor.

In addition, the photoconduction sensitivity of the photoconductive layer is inherently lower when excited by such radiations than when excited by optical rays, and consequently, the photoconductivity with respect to such radiations is usually extremely low.

In a light intensifier for radiation of the kind specified above, in order to obtain a high white-to-black ratio (contrast ratio) of the output image produced in the electroluminescent layer, it is required that the electroluminescent layer has a low impedance, and the photoconductive layer has a high dark impedance. Conventional light intensifiers for radiations are driven by alternating current energy, and consequently, the above-mentioned impedance conditions are satisfied by a large electric capacity of a thin electroluminescent layer, and a small electric capacity of a thick photoconductive layer, with mechanically formed groove openings of V-shapes and a decreased space factor of electrodes provided on the photoconductive layer.

In general, however, the mechanical working for providing the groove openings in a photoconductive layer is apt to break the photoconductive material forming the

2

layer, and such a breakage in the surface of the photoconductive layer at the side of groove openings extremely lowers the photoconduction sensitivity. Any mechanical working is thus undesirable for the purpose of highly sensitive operation.

Particularly with regard to the above-mentioned impedance conditions, the specific dielectric constant which determines the electric capacity of the photoconductive layer is usually higher than 10. Conventional photoconductive layers with groove openings formed directly therein cannot have an electric capacity other than that limited by the specific dielectric constant inherent in the material and the geometrical shape of the photoconductive layer.

The present invention contemplates overcoming the above-mentioned difficulties inevitable in conventional light intensifiers for radiations.

The present invention is characterized in that a photo-transparent electrode is disposed on one side of the electroluminescent layer, and on the other side, by intercession of an opaque layer, a current diffusion layer, and other necessary layers, a radioluminescent layer is disposed for emitting optical rays by excitation with the radiation, which layer is provided with groove-shaped or pore-shaped openings, and has a second electrode disposed on the top thereof, and in that a photoconductive layer is arranged in electrical contact with the above-mentioned second electrode and secured to the opening side of the radioluminescent layer covering the same. Voltage is applied across the photo-transparent electrode and the second electrode, and the photoconductive layer is excited by radiation directly, while the radiation passing through at least portions of the photoconductive layer and/or the electrodes causes the radioluminescent layer to emit optical rays, such emitted optical rays exciting the photoconductive layer for responding to the same.

Taking X-ray as an example of radiations, the invention will now be described.

Referring to FIG. 1, the light intensifier shown comprises a photo-transparent supporter plate 1 of transparent glass plate, for example, and it may be of a lead-containing glass capable of absorbing X-rays. The light intensifier further comprises a photo-transparent electrode 2 formed by a metal oxide film, such as of tin oxide, sprayed onto the supporter plate 1, an electroluminescent layer 3 of ZnS:Cu, Al powder for example, mixed with a bonding agent, such as epoxy resin, having a thickness of 40 μ or so, ZnS:Cu, Al being luminant in response to green colors to change in electric field, and intermediate layers 41 and 42, layer 41 being an insulating or semi-conductive opaque layer of black paint or the like, having a thickness of about 5 to 10 μ , for example. The layer 41 serves to isolate optically the electroluminescent layer 3 from a photoconductive layer 7, to be described later. The layer 42 is a current diffusion layer for facilitating mechanical working of open portions 52 of a radioluminescent layer 50 to be described later and also for causing diffusion of the photo-current to prevent stripping of output image L. This layer is formed by powder of non-linear resistance material, such as Cds:Cl for example, mixed with bonding material, such as epoxy resin for example, and has a thickness of about 100 to 300 μ , for example.

The radioluminescent layer 50 is rendered luminant by excitation of radiation, and is provided with open portions 52 in the form of parallel V-shaped grooves. The tops of the grooves are provided with electrodes 6 formed by metal vaporizing, adhesive silver paint, or the like. The photoconductive layer 7 is secured to the radioluminescent layer 50 at its side face 51 to cover the same and, at the same time, is in electrical contact with the electrodes 6.

In the embodiment shown, the photoconductive layer 7 may be formed by vacuum vaporization, or by spraying a mixture of photoconductive powder and bonding material, such as epoxy resin, diluted with a solvent, such as diacetone alcohol, to form a thin layer.

It is now assumed that the photoconductive layer 7 is formed with a photoconductive material of the CdS series activated by Cu, Cl. Photoconductive materials of the CdS series have photoconductivity even for X-rays, and have a high photoconductive sensitivity for optical ray excitation, its spectral distribution of photoconduction being in the range of 500 to 900 μ . The radioluminescent layer 50 is required to emit optical rays by the X-ray (radiation) exciting, and also to excite the photoconductive layer 7 to respond by the emitted optical rays, thus varying the impedance. Consequently, the spectral energy distribution characteristics of the optical rays should be in overlapping relation at least partly with the spectral photoconductivity distribution characteristics. Thus, if the spectral photoconductivity distribution characteristics are in the above-mentioned range of 500 to 900 μ , the spectral energy distribution characteristics of optical rays of the layer 50 should at least partly be in 500 to 900 μ . For the most desirable case, the spectral energy distribution characteristics should exist in the range of the spectral photoconductivity distribution characteristics, and the maximum integral value should be obtained when the product of the respective response value (distributed value) for every wave length has been integrated against the desired wave lengths.

For photoconductive materials of the CdS:CuCl series, X-ray luminescent phosphor, (Cd, Zn)S (solid solution of the CdS and ZnS) activated with Ag satisfies the above-mentioned condition. For example, when the layer 7 is formed by spraying powdered CdS:CuCl, which is highly sensitive to orange light, mixed with a bonding agent, such as epoxy resin, etc., to form a suspension, the layer 50 may be formed by a powder of X-ray luminescent phosphor (Cd, Zn)S:Ag which is orange luminescent, mixed with an adhesive agent, such as epoxy resin, polystyrol resin, etc. The thickness of layer 50 is selected to be large enough to have an appropriately high impedance in comparison to that of the layer 3, to lower electroluminescent output in a dark state for improving white-to-black ratio (Contrast ratio) of the output image L.

For example, the layer 50 may be of about 300 to 400 μ thickness, and the conductive adhesive agent is applied over one face of layer 50 to a thickness of about 20 to 40 μ . Then, V-shaped grooves are cut therein at pitch spacings of about 600 μ to provide openings 52. With such a construction, the space factor of electrodes 6 is lower than 1, and therefore, the layer 50 shows further high impedance by virtue of openings 52. After the radioluminescent layer 50 and electrodes 6 have thus been formed, the photoconductive layer 7 is formed thereon by spraying. The electrodes 6 are all connected to a conductor 8 in parallel relation, while the transparent electrode 2 is connected to a conductor 10. Thus, the electrodes 6 and 2 are connected across an alternating current supply source 9.

When an X-ray image X is projected onto the intensifier as shown by arrows, the impedance (resistance) of the photoconductive layer 7 decreases by the X-ray excitation. X-rays, being of high transmittivity, pass through the layer 7, and through the opening sides 51 of the radioluminescent layer 50 and electrodes 6 to excite the layer 50 which in turn generates orange light L₀. The light L₀ excites the photoconductive layer 7 covering the opening sides 51 to respond optically. Since the layer 7 is of low transmittivity with respect to light, and in addition, the layer 50 shows a behavior as one kind of light integrant, the optical rays generated in the layer 50 are wholly absorbed by the layer 7 through the opening sides 51, except those which are absorbed in the layer 50 itself, and the optical excitation is accomplished effectively.

Consequently, the photoconductive layer 7 is excited by X-rays directly, and also excited by the optical rays converted in the layer 50 from penetrating X-rays that would otherwise be lost, and operates with a higher sensitivity than ever. The photocurrent flows from electrodes 6 along opening sides 51, and diffuses through the layer 42 to render the layer 3 luminant. The X-ray image X has thus been converted and intensified to a visible image L on the layer 3.

According to the invention, mechanical working for providing openings is done only in the radioluminescent layer, but not in the photoconductive layer which can be formed by vaporizing or spraying, and consequently, the photoconductive sensitivity is never damaged. In addition, the photoconductive layer and the radioluminescent layer are of different materials, and therefore, by appropriate construction of the radioluminescent layer, its dark impedance (impedance in a dark state) can be made high, in comparison to direct working on the photoconductive layer for provision of groove openings therein, even if their geometrical shapes are the same.

For example, when the photoconductive layer is formed by a photoconductive powder of the CdS series mixed with an adhesive agent, its specific dielectric constant can be made low to a certain extent by use of an adhesive agent of low specific dielectric constant ϵ , such as, for example, polystyrol of $\epsilon=2.5$. However, unless photoconductive particles have good mutual contact, high photoconductive sensitivity cannot be obtained. Usually, the mixture proportion by volume of photoconductive powder should be about 80%, but the specific dielectric constant of photoconductive particles is higher than 10, and consequently, the specific dielectric constant of the photoconductive layer is naturally higher than 10.

According to the present invention, however, the radioluminescent layer 50 serves as an impedance. Radioluminescent particles are commingled in the layer 50, but in this case, the mixture proportion is never limited from the requirement of mutual contact of the particles as in the case of photoconductive layer. If the radioluminescent particles, such as CdZnS:Ag, have a specific dielectric constant of 10 or so, and an adhesive agent, such as polystyrol, of low specific dielectric constant of 2.5 or so, is used, there being no limit on the mixture proportion by volume, the specific dielectric constant can be made lower than 10, and as low as 2.5 or so, by decreasing the proportion by volume of fluorescent particles.

In the foregoing description, the dark impedance is considered from the side of electric capacity, but below is considered from the side of dark resistance.

Radioluminescent particles, such as (Cd,Zn)S:Ag, are of an insulating nature, and have an extremely high specific resistance. On the other hand, photoconductive materials, such as CdS:CuCl, have a dark resistance lower than the former. It is, therefore, clear that the present invention is superior to the well-known art, with respect to the specific resistance also.

In the embodiment shown in FIG. 1, the open portions 52 are in the form of equal-spaced parallel grooves, but may be of other form, such as concentric circles or spirals, and they are not necessarily V-shaped, but may be circular arc or rectangular in cross-section.

Further in FIG. 1, the photoconductive layer 7 is secured to and covers the V-shaped opening sides 51, but X-rays or other radiations of high transmittivity can pass through the layer 7 even when it is substantially thick, and the photoconductive layer 7 is allowed to fill up the openings 52. Although the photoconductive layer 7 covers the electrodes 6 in FIG. 1, it is not required, but the only requirement is that the layer 7 is in electrical connection with electrodes 6. Consequently, electrodes 6 may be exposed beyond the layer 7.

FIG. 2 shows another embodiment of the invention, in which the open portions are of pore shape. In this figure, the same reference numerals are used for indicating parts corresponding to those in FIG. 1.

Referring to FIG. 2, the open portions are regularly distributed conical pores, with their tip portions extending into the current diffusing layer 42. The photoconductive layer 7 fills up the conical-pore openings, and covers the opening sides 51, and further covers and is secured to the electrode 6 of net form.

Needless to say, the photoconductive layer 7 may not fill up the open portions, but merely cover the opening sides 51, in electrical contact with the electrode 6. The shape of the pores need not be conical, but may be cylindrical, square-cylindrical, semi-spherical, or the like.

In either of the above-described two embodiments, the groove or conical openings extend into the current diffusing layer 42, and this is desirable for effectively utilizing the impedance change in the photoconductive layer 7, and also for preventing striping or spotting of the output image by effective diffusion of the photocurrent, but this is not limitative. For example, the groove openings may extend to mid portions of the radioluminescent layer 50, or to its face in contact with the layer 42. Further, the current diffusing layer 42 may be omitted, if required.

Further in the embodiments shown, the electrodes 6 are X-ray transmittive (radiation transmittive), and the opening sides 51 form inclined surfaces, and therefore, the radioluminescent layer 50 is excited to become luminant by both of the X-rays (radiations) that pass through the portions of electrodes 6 and photoconductive layer 7, obtaining the desirable results, but the present invention is never limited to such a case only. Thus, the objects of the present invention can be accomplished principally by the radioluminescent layer 50 being excited to emit optical rays by radiation that passes through either the portion of electrodes 6 or the portion of the photoconductive layer 7.

From the foregoing, it is seen that the essential condition of the present invention is to have the radioluminescent layer excited to emit optical rays by the radiation that has passed through at least either portion of the photoconductive layer 7 or electrodes 6. It is natural that substances of the electrodes and photoconductive layer as well as shape of the open portions should be selected to satisfy the above condition.

The photoconductive layer may be a sintered layer, when glass enamel or other adhesive agents durable to high temperature are employed in the radioluminescent layer. Further, in case that the electroluminescent layer is rendered luminant by a direct current, such as a vaporized electroluminescent layer, it may be connected to a D.C. supply source for effecting direct current operation.

For use for γ -rays and other radiations than X-rays, appropriate materials should be employed, needless to say. The radioluminescent layer may be formed without employing an adhesive agent, but by sintering, etc.

What is claimed is:

1. A light intensifier for radiations comprising an electroluminescent layer, a photo-transparent first electrode disposed on one side of said electroluminescent layer, a radioluminescent layer mounted on the other side of said electroluminescent layer, a plurality of recessions in said radioluminescent layer on the far side thereof from said electroluminescent layer, at least one second electrode disposed on the top portion of the recessed radioluminescent layer, a photoconductive layer covering the recessed surface of said radioluminescent layer as well as its recessed portions, said photoconductive layer being electrically connected with said second electrode, and an electric voltage source applied across said photo-transparent first electrode and said second electrode.

2. The light intensifier according to claim 1, in which said recessions of radioluminescent layer are of groove shape.

3. The light intensifier according to claim 1, in which said recessions of radioluminescent layer are of pore shape.
